UNITED STATES PATENT OFFICE.

MARTIN MADSEN, OF MONTEREY PARK, CALIFORNIA.

PUG MILL.

Application filed April 20, 1927. Serial No. 185,222.

Heretofore the pug mills used in mixing pavement material have been constructed with bottom, side and end walls cast integral. As most of the wear in a pug mill comes upon the box and in the portion of the bottom of the box which is below the mixing paddles, the same soon becomes worn to such an extent that the box must be thrown away and a new box installed. It takes time to install a new box and involves considerable expense. It is the object of my invention to improve the pug mill by making the box thereof with a sectional bottom and with the sections reversible so that when the edges of the side portions become too much worn to function properly that such sections can be quickly and easily changed to position the comparatively unworn edges for the fully worn edges and when the second edge wears out the section can be quickly and easily replaced by a new one. Another object is to provide a removable central portion which when worn out can be quickly and easily replaced by a new one. Another object is to provide removable and adjustable discharge gates. Other objects will appear later.

In the drawings forming a part of this application:

Fig. 1 is a side elevation partly in section of my improved pug mill;

Fig. 2 is an end view, partly in section;

Fig. 3 is a top plan view with all the paddles omitted except 3;

Figs. 4 to 7 are enlarged views of parts of the mill.

Referring to the drawings the end members of the mixing box are horizontally divided and the top portions are numbered 8 and 9 and the bottom portions 10 and 11. In these end members are mounted the paddle shafts 12 and 13 which carry gears 14 and 15 that mesh with each other. The paddles are mounted on shafts 12 and 13 and except two are shown diagrammatically by dotted lines 18 in Fig. 3 and in enlarged detail in Fig. 7. The paddles comprise blades 19 having hubs 20 and collars 21 which are secured to the hubs by bolts 22. The hubs and collars have recesses 23 therein provided with toothed shaped perimeters as shown in Fig. 7 so as to position the paddles spirally or otherwise on the shafts as desired. The shafts are square in cross-section and fit into the toothed shaped perimeter. Shafts 12 and 13 are mounted in adjustable bearing

blocks 24 which are mounted on horizontal ledges 25 projecting horizontally and outwardly from the outer surfaces of the end members. These bearing blocks are adjustably positioned on the ledges by suitable bolts so as to adjust the shafts toward and from each other. The end members have projecting from their inner surfaces curved ledges 26 against which ledges the side sections of the bottom pieces of the box abut. These side bottom pieces comprise the reversible curved members 27 whose ends are rabbeted to rest against the ledges of the end members and are provided with lugs 28 having holes 29 through which bolts 30 pass to unite them to the lugs 31 on the end members. These bottom side pieces are of the same configuration so as to fit on either side and to have either edge uppermost, thereby permitting the turning of the section to substitute a less worn edge in the position formerly occupied by a greater worn edge. It will be understood that there is more wear on the bottom portion than on the top portion of these sections. This reversibility prolongs the life of usefulness of these portions of the bottom of the box. A central bottom section 32 rabbeted at the ends to fit upon the ledges of the end members and along the side edges to receive the edges of the side pieces is secured to the end pieces by suitable lugs and bolts. In the central portion of section 32 is a discharge opening 33 which when the mill is being operated is covered by a gate 34.

Gate 34 is slidably mounted upon gate bars 35, one on each side of the gate. Bars 35 are carried by brackets 36 secured to and at the corners of section 32. These brackets carry adjusting screws 37 by means of which bars 35 can be adjusted to take up any wear on the bars or on gate 34. Attached to one end of gate 34 is the gate operating bar 38 which is operated by any suitable power device. In Fig. 1 I have shown a pneumatic device 39 by means of which the gate is opened or closed.

Section 32 also has brackets 50 that project under the bottom edge of members 27 as best shown in Fig. 2. Brackets 50 carry adjusting screws 51 so that the abutting edges of 27 and 32 may be in the same plane.

The upper portion of the mixing box is composed of the upper side members 40 and 41 and end members 8 and 9. Members 40 and 41 have lips 42 that fit over the upper

edges of sections 27 and hold the upper members positioned. End members 8 and 9 have projecting forked lugs 43 in which are received the ends of rods 44 whose ends are threaded and carry nuts 45. When the parts are positioned and the nuts tightened the upper portions of the box are securely held upon the lower portions. Power is applied to shafts 12 or 13 to operate the paddles.

10 Having described my invention, I claim—

1. A pug mill comprising a mixing chamber having a sectional bottom composed of a central section having a discharge port therein, and two interchangeable reversible side members adapted to be reversed edge for edge and end for end; two paddle shafts, adjustably mounted in the end members of said chamber; paddles on said shafts; a longitudinally sliding gate adapted to control 15 said discharge port; means to adjust the position of said gate; and means to adjust the upper surfaces of the lower edges of the side bottom members with reference to the upper surface of the adjacent edges of said central member.

2. A pug mill provided with mixing chamber having a bottom composed of side mem-

bers and a central member, said central member having a discharge opening therein; said side members being of the same configuration and being adapted to be reversed edge for edge and end for end; means to adjust the lower edges of said side members with reference to the adjacent edges of said central member; a gate slidably mounted to 30 control said discharge opening; and means to adjust said gate.

3. In a pug mill, a mixing chamber having a sectional bottom composed of a central section with reversely curved surfaces and a 40 discharge opening therein; curved side bottom members, said last members being reversible side for side and end for end and interchangeable; means to adjust the upper surface of the lower edges of said last members to the plane of the upper adjacent surfaces of said central section; a gate slidably mounted to control said discharge opening; and means to adjust the position of said gate.

In witness that I claim the foregoing I 50 have hereunto subscribed my name this 8th day of April 1927.

MARTIN MADSEN.
